CLAIM

The ornamental design for a watch for attachment to a shoe, as shown and described.

DESCRIPTION

FIG. 1 is a front perspective view of a watch for attachment to a shoe showing my new design;

FIG. 2 is a front elevational view thereof, the rear being a mirror image of the front shown in FIG. 2;

FIG. 3 is a side elevational view thereof, the side opposite being a mirror image of the side shown in FIG. 3;

FIG. 4 is a top plan view thereof; and,

FIG. 5 is a bottom view thereof.

FIG. 1

FIG. 2

FIG. 3

FIG. 4

FIG. 5
